HAIR DRYING APPLIANCE

Joseph Matys, New Bedford, Mass.

Application April 29, 1937, Serial No. 139,785

3 Claims. (CL 34—26)

The invention relates to a hair drying appliance and more especially to drying applicators for use in drying the hair after the waving of the same, either permanent or otherwise.

The primary object of the invention is the provision of an appliance of this character, wherein through the use of the invention, the hair upon the head of a person, after the waving thereof or curling of the same can be readily and easily dried through air currents under pressure and suction with the result that quick drying of the hair will be had without liability of disturbing the strands of the hair set under the waving or curling thereof and particularly where a net is worn upon the head and confining the hair for its setting, the appliance being of novel construction and can be readily handled for proper placement for drying purposes.

Another object of the invention is the provision of an appliance of this character, which is simple of construction, thoroughly reliable and efficacious in operation, readily and easily handled, eliminating discomfort to a person having the hair dried after receiving a wave treatment, readily and easily handled by an operator, and inexpensive to manufacture and install.

With these and other objects in view, the invention consists in the features of construction, combination and arrangement of parts as will be hereinafter more fully described, illustrated in the accompanying drawing and pointed out in the claims hereunto appended.

In the accompanying drawing:

Figure 1 is a perspective view of the head of a person having received hair waving treatment showing the appliance constructed in accordance with the invention and inserted in the hair for drying purposes.

Figure 2 is a top plan view of the frame.

Figure 3 is a sectional view taken on the line 3—3 of Figure 2.

Figure 4 is a sectional view taken on the line 4—4 of Figure 2.

Figure 5 is a sectional view taken on the line 5—5 of Figure 2.

Similar reference characters indicate corresponding parts throughout the several views in the drawing.

In practicing my invention, as illustrated in the drawing, I provide a pectiniform frame 5 adapted to be inserted into the hair adjacent the scalp of a person having received hair waving treatment. The frame is fashioned with two groups of tines 6 and 7 respectively, said tines being

hollow and profusely perforated and with the tines 6 arranged alternately with respect to the tines 7. The frame is also fashioned with a pair of conduits 8 and 9 communicating with the tines 6 and 7 respectively and with said conduits arranged one adjacent the other and connected to the inner ends of the respective tines as clearly illustrated in the drawing. The conduit 8 and 9, between their end, are provided with communicating couplings 10 and 11 respectively and which 10 extend in an opposite direction with respect to the tines.

As diagrammatically illustrated in Figure 1 of the drawing, I provide a blower 12 having outlet and inlet connections 14 and 15 respectively 15 and with the outlet connection 14 interiorly fitted with an electric heating coil 16 for warming or heating air discharged therethrough. The couplings 10 and 11 are connected to the outlet and inlet connections 14 and 15 respectively of the 20 blower by means of hose 17 whereby upon operation of the blower heater air is supplied to the tines 6 through the conduit 8 and air is withdrawn from the tines 7 through the conduit 9.

In use, the frame is inserted within previously 25 treated and waved hair with the tines arranged adjacent the scalp whereupon a net N is applied over the hair to hold the same in a fixed condition during setting thereof as is customary in hair waving treatments. When the frame is thus 30 arranged, the blower is operated to supply heated air to the tines 6 and to withdraw air from the tines 7, the supplying and withdrawing of the air from the tines being simultaneous. Due to one group of the tines being disposed in pair- 35 wise correlation with the tines of the other group, heated air is circulated between the tines and adjacent the scalp, thus effecting a drying of the hair without disturbing the same while in set condition.

What is claimed is:

1. An appliance of the character described, comprising, a pectiniform frame adapted to be inserted into the hair adjacent the scalp and fashioned with groups of perforated hollow tines 45 with the tines of one group arranged alternately with respect to the tines of the other group, and conduits communicating with said groups respectively, said conduits adapted for connection to heated air-supply and suction-creating means 50 respectively for supplying air to one of said groups and withdrawing air from the other of said groups simultaneously.

2. An appliance of the character described, comprising, a pectiniform frame adapted to be 55

inserted into the hair adjacent the scalp and fashioned with groups of profusely perforated hollow tines and with the tines of one group interposed with respect to the tines of the other group, independent conduits communicating with said groups respectively, and means carried by said conduits for connecting said conduits to heated air-supply and suction-creating means respectively for supplying air to one of said groups and withdrawing air from the other of said groups simultaneously.

3. An appliance of the character described,

comprising, a pectiniform frame adapted to be inserted into the hair adjacent the scalp and fashioned with groups of perforated hollow tines with the tines of one group disposed in pairwise correlation with the tines of the other group, and conduits communicating with said groups respectively, said conduits adapted for connection to heated air-supply and suction-creating means respectively for supplying air to one of said groups and withdrawing air from the other of said groups simultaneously.

JOSEPH MATTYS.
